UNITED STATES PATENT OFFICE.

AUGUSTE E. CHARBONNEAUX, OF SAN FRANCISCO, CALIFORNIA.

EXPLOSIVE.

1,093,767.

Specification of Letters Patent. Patented Apr. 21, 1914.

No Drawing.

Application filed May 24, 1913. Serial No. 769,602.

To all whom it may concern:

Be it known that I, AUGUSTE E. CHARBONNEAUX, a citizen of the Republic of France, residing at San Francisco, in the county of San Francisco and State of California, have invented new and useful Improvements in Explosives, of which the following is a specification.

The object of the present invention is to provide an explosive the action of which will be rapid and certain and accompanied by perfect oxidation, so that the explosion thereof is followed by practically no smoke.

In preparing this explosive I obtain ammonium sulfonate of naphthalene by treating naphthalene in the usual manner with strong sulfuric acid and then neutralizing with strong ammonia. I then take five parts by weight of the ammonium sulfonate of naphthalene, ten parts of potassium chlorate and one part of potassium permanganate. These three ingredients which are in pulverized form, I thoroughly intermingle to form the complete explosive.

I find that ammonium sulfonate of naph-

thalene forms an ingredient in an explosive which can be oxidized very rapidly, and this oxidation is completely effected by the employment of potassium permanganate in addition to potassium chlorate, the supply of oxygen given up by potassium permanganate being proportionately large. The potassium permanganate therefore effects perfect combustion, so that no smoke follows the explosion, and the full energy of the combination of the ingredients is obtained.

I claim:

1. An explosive consisting of an ammonium sulfonate of a hydrocarbon, potassium chlorate and potassium permanganate.
2. An explosive consisting of ammonium sulfonate of naphthalene and potassium chlorate and potassium permanganate.

In testimony whereof I have hereunto set my hand in the presence of two subscribing witnesses.

AUGUSTE E. CHARBONNEAUX.

Witnesses:

FRANCIS M. WRIGHT,
D. B. RICHARDS.
